UNITED STATES PATENT OFFICE.

ERICH P. KEPPELMANN, OF MCKEESPORT, PENNSYLVANIA.

SPROCKET-WHEEL.

No. 836,044.

Specification of Letters Patent.

Patented Nov. 13, 1906.

Application filed February 8, 1906. Serial No. 300,175.

To all whom it may concern:

Be it known that I, ERICH P. KEPPELMANN, a citizen of the United States, residing at McKeesport, in the county of Allegheny and State of Pennsylvania, have invented a new and useful Improvement in Sprocket-Wheels, of which the following is a specification.

This invention relates to a novel form of construction of sprocket-wheels, said wheels being adapted for use both as drive and driven wheels.

The object of the invention is a sectional sprocket-wheel in which the two sections rotate about a common axis and engage the same chain, the teeth of the sections alternating, the strain or torque being sustained by a tooth of one section while an adjacent tooth of the coacting section is in the act of 20 engaging or disengaging a link of the chain.

The invention consists of a sprocket-wheel formed of two circular interlocking sections each carrying the same number of teeth, the said teeth alternating when the sections are 25 assembled together, all of the teeth describing the same path and all meshing with links of one common chain, and the invention further consists in a sprocket formed of a plurality of sections having concentrically-arranged hubs and a clearance provided between the said sections.

In the accompanying drawings, Figure 1 is a perspective view showing the parts assembled to form a complete sprocket-wheel. 35 Figs. 2 and 4 are face views of different sections, respectively, the sections being adapted to interlock. Figs. 3 and 5 are sections on the lines 3 3 and 5 5, respectively, of Figs. 2 and 4. Fig. 6 is a diametrical section 40 through the sprocket-wheel, the sections being assembled. Fig. 7 is a detail view, partly in section and partly in elevation, showing the clearance and spring, the latter being in elevation. Fig. 8 is a diagrammatic plan of 45 a portion of the periphery of the wheel.

In constructing my sprocket-wheel I employ two sections A and B, which sections comprise substantially the same parts, though differing slightly in construction.

50 The section A comprises a hub portion A', which extends a considerable distance upon one side of the body of the section to form a bearing for a hub portion of the section B. It is provided with a bore A², adapted to fit 55 the shaft to which the sprocket-wheel is to be keyed or otherwise secured and with which it

will rotate. The section A is also formed on its inner face with a plurality of alternating recesses A³ and projections A⁴, the latter carrying the sprockets A⁵, which may be of any 60 desired number.

The section B comprises a hub portion B', having a bore B², adapted to receive the hub portion A' of the section A. The section B is otherwise the counterpart of section A, 65 having recesses B⁴ on its inner face adapted to receive the projections A⁴ of the section A and having also projections B³, adapted to rest in the recesses A³ of the section A. It is 70 also provided with sprockets B⁵, which when the sections are assembled together alternate with the sprockets A⁵ of the section A. When so assembled, a clearance C is left between the inner faces of the projections A⁴ and B³ and the walls of the respective recesses in 75 which they fit. This clearance permits the arrangement of a curved leaf-spring C' between the projections of one section and those of the other and, furthermore, allows a limited play of the sections with reference 80 to each other, the section B having a limited movement on the hub portion of section A independent of movement of the section A and of the shaft to which A is keyed. This permits the link to be straightened out as it 85 leaves the sprocket and to be "kinked" as it engages the sprocket with greater ease than on the ordinary form of sprocket-wheel, the sprocket of one section sustaining the torque and taking up the strain as the adjacent 90 sprocket of the other section engages or releases a link of the chain. The springs C' aid in equalizing the torque transmitted at any given instant by the two sections.

Having thus fully described my invention, 95 what I claim as new, and desire to secure by Letters Patent, is—

1. A sprocket-wheel formed of interlocking sections adapted to rotate on a common axis and having teeth adapted to engage a 100 common chain.

2. A sprocket-wheel formed of interlocking sections, one of said sections having a hub portion adapted to be keyed to a shaft and the other section having a hub portion adapted to rotate freely upon the hub of the first-mentioned section, and sprocket-teeth carried by the sections and adapted to mesh with a common chain. 105

3. A sprocket-wheel comprised of two sections, one of said sections having a hub portion said hub having a bore adapted to fit a 110

shaft, and the said hub forming a bearing for the other section, and alternately-arranged sprocket-teeth on the section adapted to mesh with a chain common to all of the teeth 5 of the said sprocket-wheel.

4. A sprocket-wheel of the kind described comprising sections having coacting projections and recesses on their inner faces, said sections having hub portions and one of said 10 sections rotating on the hub portion of the other, a clearance being formed between the sections, sprocket-teeth formed on the projections of each section, and springs arranged in the clearance between the projections.
- 15 5. A sprocket-wheel comprising a section having a hub portion projecting laterally beyond the body of the section, the inner face of the said section having alternating projec-

tions and recesses thereon, sprocket-teeth formed on the projections, a second section 20 having a hub portion adapted to engage the projecting hub portion of the first section, the said section having on its inner face projections and recesses adapted to interlock with the first section, sprocket-teeth carried 25 by the projections of the section and adapted to alternate with those of the first section, and springs arranged between the projections of the two sections, the second-mentioned section having a limited movement with respect to the first. 30
